UNITED STATES PATENT OFFICE.

JAMES HENRY CUMPSTON, OF DALLAS, TEXAS.

GUN-CLEANING DEVICE.

1,427,582.

Specification of Letters Patent. Patented Aug. 29, 1922.

Application filed December 14, 1921. Serial No. 522,274.

To all whom it may concern:

Be it known that I, JAMES HENRY CUMPSTON, a citizen of the United States, and a resident of Dallas, in the county of Dallas 5 and State of Texas, have invented a new and Improved Gun-Cleaning Device, of which the following is a full, clear, and exact description.

This invention relates to improvements in 10 gun cleaning devices, particularly to a device for cleaning rifles.

An object of the invention is to provide an improved means for retaining a cleaning 15 rag in unwrinkled position upon the end of a ramrod, and to provide improved means for tightly wrapping the rag around the rod.

A still further object is to provide means 20 for preventing the rag from slipping off the rod before the same is inserted in the barrel of a rifle, and to provide a cleaning device which will be simple and practical in construction, efficient in use, and which can be manufactured with comparative economy.

With these and other objects in view, the invention consists in certain novel features of construction and combinations and arrangements of parts as will be more fully 30 hereinafter described and pointed out in the claims.

In the accompanying drawings:

Figure 1 is a view in section through the breech end of a rifle barrel showing the 35 manner of use of my improved cleaning apparatus;

Figure 2 is a perspective view of the cleaning apparatus;

Figure 3 is a perspective view of the tip; 40 and

Figure 4 is an enlarged sectional view upon the line 4-4 of Figure 2.

Referring in detail to the drawings, I have used the reference numeral 1 to designate a 45 ramrod having in one end a screw threaded recess or pocket 2. A detachable tip, indicated at 3, is formed at one end with a reduced threaded nipple or extension 4, which may be screwed into the pocket to firmly 50 attach the tip to the rod. It will be noted that this tip at its free end is longitudinally slit, as indicated at 5, and is externally threaded, as shown at 6, for a purpose which will hereinafter appear. That portion of the 55 tip between the slit 5 and the nipple 4 is milled, knurled, or otherwise treated to pro-

vide a roughened surface 7 which facilitates the manual turning of the tip. The slit 5 in the end of the tip is adapted to serve as an anchorage for one end of a cleaning rag, 60 indicated at 8, which may be wrapped around the tip, as seen most clearly in Figure 4, the threaded portion 6 of the tip biting into the soft cloth of the rag and firmly holding the same against wrinkling, or slipping 65 on tip.

It has been previously stated that two objects of the invention were to provide improved means for facilitating the wrapping of the rag tightly around the tip and to 70 provide means for preventing the accidental dislodging of the rag. These objects are accomplished by the use of a cylindrical sleeve 9 which is longitudinally slit or split, as indicated at 10. The sleeve is externally 75 tapered at one end, the tapered portion being indicated by the reference numeral 11 and a plurality of longitudinal grooves 12 in the outer face of the sleeve facilitate its manual turning or holding.

The manner of use of the apparatus is as follows: The tip 3 is first connected to the ramrod 1 by screwing the nipple 4 into the pocket 2. The cleaning rag 8 then has one 85 end passed through the slot 5 in the tip and wrapped once or twice around the tip. The sleeve 9 is then slipped over the tip, the unwrapped portion of the rag passing edge-wise through the slit 10 in the sleeve 9, as seen in Figures 2 and 4. In order to finish 90 the wrapping of the rag 8, the sleeve 12 may be held while the ramrod is turned or the tip 4 may be held while the sleeve is turned, this turning of the sleeve insuring the tight 95 wrapping of the rag about the tip.

In using the cleaning apparatus, the sleeve and tip are inserted in the cartridge chamber 13 of a rifle barrel 14, the sleeve and tip entering the chamber until the tapered end of the sleeve abuts against the 100 tapered shoulder 15 at the forward end of the cartridge chamber and holds the sleeve against further movement. Further pushing of the ramrod will then force the tip into the barrel of the gun with the rag 105 wrapped tightly about the same. It is of course to be understood that the rag is treated with any suitable grease or cleaning material for cleaning the barrel of the gun.

Although I have illustrated one of the 110 preferred embodiments of my invention, it will be apparent that various slight changes

and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

10 In closing it might be well to note that while I have shown the cleaning device in operation at the breech end of a rifle, the device might be used equally well when inserting the ramrod through the muzzle of 15 the gun.

I claim:

1. A gun cleaning device, including a rod threaded and longitudinally split adjacent its tip, whereby to facilitate the anchoring 20 of a cloth patch, means facilitating the winding of a patch around said rod, and said means including a split sleeve of greater internal diameter than the external diameter of the rod.
2. In a gun cleaning apparatus, a detachable tip for ramrods having a longitudinal slit therein extending from one end of the tip throughout the major part of its length, a cleaning patch anchored in the slit, a split 30 sleeve around the tip, the split in the sleeve receiving the free end of said patch, and means facilitating the manual turning of the sleeve and tip to effect winding of the patch about the tip.
3. In a gun cleaning apparatus, a detach-

able tip for ramrods having a longitudinal slit therein extending from one end of the tip throughout the major part of its length, a cleaning patch anchored in the slit, a split sleeve around the tip, the split in the sleeve 40 receiving the free end of said patch, and means facilitating the manual turning of the sleeve and tip to effect winding of the patch about the tip, said means including an exterior roughened surface on the tip, said 45 sleeve having longitudinal grooves in its outer face.

4. A gun cleaning device comprising a member longitudinally split and externally threaded throughout the major portion of 50 its length to facilitate the anchoring of a cleaning patch wrapped thereabout, and a split wrapping sleeve of greater internal diameter than the external diameter of said member adapted to hold a patch in position 55 prior to the insertion of the member into a rifle barrel.

5. A gun cleaning device comprising a member longitudinally split and externally threaded throughout the major portion of 60 its length to facilitate the anchoring of a cleaning patch wrapped thereabout, and a split wrapping sleeve of greater internal diameter than the external diameter of said member adapted to hold a patch in position 65 prior to the insertion of the member into a rifle barrel, and manually operable means for actuating the member.

JAMES HENRY CUMPSTON.
